US00D912696S

(12) **United States Design Patent** (10) **Patent No.:** **US D912,696 S**
(45) **Date of Patent:** **** Mar. 9, 2021**

(54) **ELECTRONIC DEVICE WITH GRAPHICAL USER INTERFACE**

(71) Applicant: **Apple Inc.**, Cupertino, CA (US)

(72) Inventors: **Kevin Will Chen**, Cupertino, CA (US);
Alan C. Dye, San Francisco, CA (US);
Christopher I. Wilson, San Francisco, CA (US)

(73) Assignee: **Apple Inc.**, Cupertino, CA (US)

(**) Term: **15 Years**

(21) Appl. No.: **29/741,106**

(22) Filed: **Jul. 9, 2020**

Related U.S. Application Data

(63) Continuation of application No. 29/663,025, filed on Sep. 11, 2018, now Pat. No. Des. 891,454.

(57) **CLAIM**

The ornamental design for an electronic device with graphical user interface, as shown and described.

DESCRIPTION

FIG. 1 is a front view of an electronic device with graphical user interface showing the claimed design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The dashed broken lines in FIGS. 1-6 show portions of electronic device with graphical user interface that form no part of the claimed design.

1 Claim, 4 Drawing Sheets
